DRESSING AND BASTING SPOON

James J. Melich and Edwin G. Melich,
Chicago, Ill.

Application January 28, 1952, Serial No. 18,264

Term of patent 14 years

(Cl. D44—29)

To all whom it may concern:

Be it known that we, James J. Melich and Edwin G. Melich, citizens of the United States, residing at Chicago, in the county of Cook and State of Illinois, have invented a new, original, and ornamental Design for a Dressing and Basting Spoon, of which the following is a specification, reference being had to the accompanying drawing, forming part thereof.

Fig. 1 is a view in perspective, on a reduced scale, of a dressing and basting spoon, showing our new design.

Fig. 2 is a full sized plan view of the lower part of the spoon;

Fig. 3 is a full size plan view of the upper part of the spoon;

Fig. 4 is a rear edge view;

Fig. 5 is a front edge view; and
Fig. 6 is a bottom plan view.

We claim:

The ornamental design for a dressing and basting spoon, as shown.

JAMES J. MELICH.
EDWIN G. MELICH.
